DRY CLEANING MACHINE

Robert McIntyre Coram, Winnipeg, Manitoba,
Canada

Application January 25, 1936, Serial No. 60,858

6 Claims. (Cl. 74—218)

The invention relates to dry cleaning machines wherein clothes are cleaned by a solvent solution and the principal object of the invention is to produce a drive mechanism for a machine which will wash, tumble, extract and deodorize suits, dresses, coats, etcetera, without removal from the machine during the various operations.

A further object of the invention is to provide a driving means for the tub whereby it can be intermittently reversed, or driven in one direction only at high speed, and said means may be changed to either drive while the machine is in operation.

A further object of the invention is to provide a hand controlled belt tightener to be used when the machine is under heavy load.

A further object of the invention is to extract the solvent from the clothes by centrifugal force and driven heated air, and recover the same from the air.

With the above important objects in view, which will become more apparent as the description proceeds, the invention consists essentially, in the arrangement and construction of parts hereinafter, more particularly described, reference being had to the accompanying drawings in which:

Figure 1 is a side view of the machine.

Figure 2 is a front view of the machine.

Figure 3 is a plan view of the machine.

Figures 4 and 5 represent enlarged upper and lower vertical sections taken on the line 4—4, Figure 1.

Figure 6 is an enlarged section of one end of the tumbling tub drive shaft and associated parts, including clutches.

Figure 7 is an enlarged vertical section through the tumbling tub reverse mechanism showing the reverse control plate in dotted outline, the said section being taken on the line 7—7, Figure 1.

Figure 8 is a vertical section taken on the line 8—8, Figure 7.

Figure 9 is an enlarged vertical section of the fan control clutch and associated parts.

In the drawings, like character of reference indicate corresponding parts in the several figures.

A pair of standards 1 and 2 support a hollow cylindrical casing 3 formed from two semi-circular members 4 and 5 and they also support a main cross shaft 6 through a pair of exterior ball bearings 7. The said shaft passes centrally through the casing 3 with suitable packing boxes 8 at either side. A pair of pulleys 9 and 10 (see Fig. 6) are mounted on one end of the shaft,

the pulley 9 being carried by a ball bearing 11, backed by a sleeve 12, and the outer side thereof is provided with an enlarged flange 13. The pulley 10 is also provided, on the outer side, with an enlarged flange 14. A circular plate 15, having a boss 16, is fastened to the shaft and the end of the said shaft abuts the end of a small extension 17. This extension is interiorly screw threaded, is of less diameter than the shaft and is provided, on the shaft abutting end, with a flange 18 of the same diameter as the shaft. This flange is received within the boss 16, which hooks thereover to prevent its withdrawal. A hand wheel 19 is fastened by a set screw to the extension 17, and in the turning of this hand wheel, the extension revolves.

A disk 20 is mounted on the shaft, between the pulleys, and centrally is secured to a bar 21 which passes through a slot 22 in the shaft. The end of the shaft is counterbored at 23 to the slot 20 and a rod 24 therein connects the bar 21 with the extension 17 in which it is centrally screwed. Both sides of the disk 20 are provided with clutch facings 25 and 25' and the side of the disk 15, opposite the flange 14, is also provided with a clutch facing 26.

From the above it will be apparent, that if the hand wheel 19 is rotated in one direction, the disk 20 will press the left hand clutch facing 25 into engagement with the pulley 9, while if the hand wheel is turned in the opposite direction, the disk 20 will press the right hand clutch facing 25' against the side of the pulley 10 and the flange 14 will press against the facing on the disk 15.

On the main shaft 6 and within the cylindrical casing 3, a tumbling tub 27 is securely mounted. This tub is of a hollow drum shape, the walls and circumferential face thereof, are perforated and the interior is provided with four cross partitions 28 which divides the interior into four compartments. Each compartment is provided with a clothes receiving opening (not shown) in the circumferential face of the tub. These openings are closed, in the operation of the machine, by a pair of doors 30 and 31. The door 31 is hinged on the adjacent under side to the interior of the tub circumferential face while hinges on the outer face of the doors pivot them together. Suitable exterior locking means holds them closed.

The semi-circular member 4 is provided on its front outer circumferential face with a circular boss 44 which encloses a circular clothes entrance opening (not shown). An angle shaped plate 46 is fastened to one side of the member 4 and pro-

jects upward a short distance and pivotally receives a cross bar 47 which passes across the opening and rests within a catch 48 mounted on the other side of the member 4. This cross bar is centrally tapped to receive the threads of a screw 49 which is rotatably controlled by a hand wheel 50. The opposite end of the screw extends below the cross bar and pivotally supports a circular closure disk 51 which is adapted to contact with the face of the boss 44 and close the clothes entrance opening.

A thermometer 45' is connected to the top of the casing 3 to register the temperature therein.

A rectangular shaped condensing box 52 is mounted at one side of the machine and projects above the casing 3. An extension projects downward from the rear end of this box and is fastened to the casing 3 where an opening (not shown) is provided intercommunicating with the interior thereof. A fan casing 76 is fastened to the side of the box 52 and communicates therewith. The shaft of this fan is exteriorly provided with a pulley 75'. The lower part of the fan is supported and is in direct communication with a duct (not shown) mounted on the rear portion of the semi-circular member 4. This duct passes completely thereacross and communicates with the interior of a casing 78 mounted on the side of the said member 4. This casing interiorly supports a steam heating unit 79. An opening (not shown) is provided in the side of the semi-circular member 4 and connects the lower part of the casing 78 with the interior of the casing 3.

From the above it will be apparent that when the fan is operated, air will be drawn through the condensing box, forced through the duct, then past the heating unit into the casing 3 where, after passing through the clothes, it will re-enter the condensing box for a purpose later described.

A pair of bearings 87 are mounted on the upper part of the member 4 and rotatably support a crossshaft 88. The outer end of this crossshaft supports a pulley 89 which directly drives the pulley 9 through a belt 90. Between the bearings, the shaft carries a wide pulley 91 and a narrower pulley 92, both securely fastened to the shaft (see Fig. 9). A further pulley 93 is freely mounted on the shaft and is connected through a belt 93' to the fan pulley 75'. Between the pulleys 93 and 92, a disk 94 is mounted, this disk being similar to the disk 20, having a bar 95 passing through a slot in the shaft and controlled by the end shifting of a rod 96 passing lengthwise through the interior end of the shaft 88. A wheel 97 is rotatably mounted on the end of the shaft 88 and is prevented removal therefrom by a pair of semi-circular plates 98 fastened to the inner side of the wheel and riding in an annular groove around the shaft. The rod 96 is screw threaded through the wheel 97 and when this wheel is turned in one direction, the end shifting of the rod 96 will cause the disk 94 to drive the pulley 93 through a friction facing therebetween and when the wheel is rotated in the opposite direction, the pulley will be released.

A further pair of bearings 99 and 99' are mounted on the semi-circular member 4 (see Fig. 7) and rotatably support a shaft 100. The outer end of this shaft is provided with a driving pulley 101 which directly drives the pulley 10 through a belt 102. An idler pulley 103 rides on the belt and is pivotally supported through a

crank 104, swung from the shaft 100. A further pulley 105 is securely fastened to the shaft 100, between the bearings, and on either side of this pulley, a pair of further pulleys 106 and 107 are freely mounted. A crossed belt 108 connects the pulley 106 to the pulley 91 and a straight belt 109, which is partly running on the pulley 107 also connects the pulley 91 with the pulley 105. A worm 110 is rotatably mounted on the shaft 100 and is connected to the hub 10 of the pulley 107 through a dog 111 (see Fig. 4). This worm is adapted to revolve a gear 112 mounted on a plate 113 formed as part of the bearing 99'. The plate 113 also supports a small shaft 114 (see Fig. 8) which is parallel to the shaft 100, and this shaft slidably carries a reverse control plate 115 having two converging flanges 116. An eccentric pin 117 projects from the gear 112 and is adapted to be received between the flanges 116, and in the rotation of the gear, the pin will end shift the reverse control plate on the shaft 114. A strap 118 passes from the reverse control plate and connects to a bar 119, slidably carried in bearings 120 from the plate 113. A control bar 121 is fastened to the inner end of the bar 119 and this control bar is provided with a pair of oppositely positioned links 122 which span the belts 108 and 109.

From the above it will be apparent that when the pulley 91 is driven, the pulley 105 will rotate the shaft 100 while the pulley 107 will rotate the worm 110 and drive the gear 112. As this gear turns, the reverse control plate will end shift the bar 119 and in so doing, will move the belt 109 completely onto the pulley 107 and the belt 108 completely onto the pulley 105 and so reverse the direction of the shaft 100. In the continued movement of the gear 112, the belts will be brought back to the original position, again reversing the shaft 100.

The lower part of the casing 3 is provided with a trough 123 (see Fig. 5) which leads to the open end of a valve 124, screwed into the lower side of the casing. A U shaped trap 125 is connected to a settling tank 126. Should any refuse collect in the trap, suitable cleanout plugs 127 and 128 are provided.

The settling tank is supported, at the front end, by lugs 129 which are fastened to the standards 1 and 2 and it is positioned directly under the casing 3. The rear end of the tank is supported by a drain pipe 130 which connects to a distilling tank 131 supported in a pair of frames directly at the rear of the standards 1 and 2. The upper part of the distilling tank frames support a solvent tank 137. A condensing tank 139 is supported on the top of the solvent tank and its upper part forms a support for an electric motor 141 which drives the pulley 92 through a belt 142. A pipe 143 is connected between the bottom of the solvent tank and the casing 3 and this pipe is at a slight upward slant and controlled through a valve 144.

A source of cold water supply (not shown) is connected to a pipe 152 which passes back along the side of the machine, across between the casing 3 and the distilling tank 131 to the other side where it passes up to a valve 153. This valve, through a pipe 154, controls the entrance of water into one end of the heating unit. The other end of the unit is connected to which is again connected through a T to a pipe 156 which passes back to a valve 157. A pipe from this valve is connected to a drain (not shown).

The pipe 152 is also connected through a valve 75

(not shown) with the bottom of the box 52 which is water jacketed. A pipe (not shown) is connected to the upper end of said jacket and leads to a drain (not shown).

5 A pipe 163 is provided at the front of the machine, below the casing 3, and is adapted to be connected to a source of steam (not shown). This pipe is connected to a valve 164. The steam passes from this valve to a pipe 166 and from 10 there to the pipe 154, through the heating unit and then passes back to the original source through a valve 167.

15 A drain pipe 174 connects with the bottom of the box 52 and leads to a tank 175 which is provided with a sight glass 176. A pipe (not shown) connects this latter tank with the settling tank.

The operation of the machine and drives will now be described.

20 The compartments are filled with clothes. The valve 144 is turned on causing solvent to flow into the casing 3. When a pre-determined height is reached the valve 144 is shut off. The motor 141 is then started.

25 The motor drives the pulley 92 through the belt 142, which in turn, drives the shaft 88 and the pulleys 89 and 91. Through the two belts 108 and 109, the operations of which have been described, the pulley 91 drives the pulley 101 in first one direction and then the other, and 30 through the belt 102, the motion is transmitted to the pulley 10. The pulley 10, which is connected to the main cross shaft 6, drives the tumbling tub. Under this continually reversing drive, the tub splashes the solvent through the clothes, the solvent entering the tub through the 35 perforations, and as the solvent runs out the dirt from the clothes is taken with it.

40 The valve 124 is then opened to permit the solvent to escape into the settling tank 126 and, while the machine is still running, the hand wheel 19 is rotated to alter the drive of the shaft 6 from the pulley 10 to the pulley 9, which is driven by the belt 90 from the pulley 89. Accordingly, the tumbling tub will now be driven in one direction at high speed. At this time, a 45 bar 183 (see Fig. 1) may be drawn ahead by the operator and through a lever 184, an idler pulley 185 will ride the belt 90 and tighten it to prevent slippage. The fast rotating tumbling tub, through centrifugal force, extracts most of the 50 liquid solvent from the clothes.

55 The valve 124 is then shut and a flat bar 186, (see Fig. 3), pivoted at 187 to the casing of the fan, is pressed down against the wheel 97. As the shaft 88 is turning at this time, the friction developed against the wheel 97 causes it to turn 60 slower than the shaft 88 and accordingly, the rod 96 is end shifted and moves the clutch disk 94 which operates to connect the shaft 88 with the pulley 93 and cause the operation of the fan through the belt 93'. Accordingly, air is driven from the fan casing through the duct casing, 65 through the casing 78 into the casing 3, through the clothes and back into the fan casing.

70 The operator then allows steam to pass through the heating unit and heat the passing air. When the heat of the air increases to a given temperature, it vaporizes the solvent in the rotating clothes and this gas passes along with the air. As cold water is passing through the jacket of the box 52 at this time, the low temperature 75 condenses the solvent gas which precipitates into liquid and passes down the pipe 174 to the settling tank 126.

75 When the above operations are completed, the

operator permits cold water to pass through the heat unit. This cools the passing air and the casing 3 is brought back to atmospheric temperature. The motor is shut off. The clothes are then removed and the machine is ready for the 5 next batch.

What I claim as my invention is:

1. In a drive mechanism for a dry cleaning machine having a clothes receiving tumbling tub mounted on a shaft for rotation within a solvent receiving casing, a power driven shaft mounted on the machine, a countershaft mounted on the machine, drive means connecting said power driven shaft with said countershaft to rotate the latter shaft in one direction, a second drive means 10 connecting said power driven shaft with said countershaft to rotate the latter shaft in the opposite direction, automatic control means for disconnecting one drive means from said countershaft and connecting the other drive means 15 thereto and for periodically reversing said connections, direct drive means between the said power driven shaft and the said tumbling tub shaft, drive means between the countershaft and the tumbling tub shaft, and clutch means 20 mounted on said tumbling tub shaft for selectively disconnecting one of said tumbling tub drive means and connecting the other drive means to said tumbling tub shaft.

2. In a drive mechanism for a dry cleaning 25 machine having a clothes receiving tumbling tub mounted on a shaft for rotation within a solvent receiving casing, a power driven shaft mounted on the machine and provided with a pulley, a countershaft mounted on the machine and supporting three pulleys, one of which is fastened to the said countershaft and the other two being loose thereon, a straight belt connecting the pulley on the power driven shaft with one of said pulleys on the countershaft, a crossed belt connecting the pulley on the power driven shaft with another of said pulleys on the said countershaft, means operated by said pulleys on the countershaft for passing one of said belts onto the fixed pulley and passing the other belt onto a loose pulley and for periodically reversing the 40 said operation, drive means connecting said countershaft with said tumbling tub shaft, direct drive means connecting said power driven shaft with said tumbling tub shaft, and clutch means 45 mounted on said tumbling tub shaft for selectively disconnecting one of said tumbling tub drive means and connecting the other drive means to said tumbling tub shaft.

3. In a dry cleaning machine having a clothes receiving tumbling tub wherein clothes are washed and the cleaning fluid later extracted therefrom, a driving mechanism for said machine comprising, a power driven shaft mounted on the machine, a pulley mounted on said power shaft and drive means connecting said shaft with the shaft of said tumbling tub, a countershaft mounted on said machine and supporting three pulleys, one of which is fastened to said countershaft and the other two being idle thereon, a straight belt connecting the pulley on the power driven shaft with one of said pulleys on the countershaft, a crossed belt connecting the pulley on the power driven shaft with another of said pulleys on said countershaft, guides controlling both belts, a worm mounted on said countershaft and driven by one of said idler pulleys, a worm wheel mounted adjacent said worm, operated thereby, and eccentric means carried by said worm wheel and connected to said belt guides 55

for passing one of said belts onto the fixed pulley and passing the other belt onto an idler pulley and for periodically reversing the said operation, drive means connecting said countershaft with said tumbling tub shaft, and clutch means mounted on said tumbling tub shaft for selectively connecting said shaft to either the power driven shaft or to the countershaft drives.

4. In a dry cleaning machine having a clothes receiving tumbling tub wherein clothes are washed and the cleaning fluid later extracted therefrom, a driving mechanism for said machine comprising, a power driven shaft mounted on the machine, drive means connecting said power shaft with the shaft of said tumbling tub, a counter shaft mounted on said machine and drive means connecting said countershaft with said tumbling tub shaft, means for driving the countershaft in opposite directions, respectively, comprising, driving means between said countershaft and said power shaft, a second disconnected reverse drive means between said countershaft and said power shaft, automatic control means for disconnecting the first mentioned drive means from said countershaft and connecting the second mentioned drive means thereto and for periodically reversing said connections, and clutch means mounted on said tumbling tub shaft for selectively connecting said shaft to either the power shaft or to the countershaft drives.

5. In a dry cleaning machine having a clothes receiving tumbling tub wherein clothes are washed and the cleaning fluid later extracted therefrom, a driving mechanism for said machine comprising, a power driven shaft mounted on the machine, a belt drive connecting said power shaft with the shaft of said tumbling tub, a countershaft mounted on said machine having

a belt drive to said tumbling tub shaft, means for driving the countershaft in opposite directions, respectively, comprising, a belt drive between said countershaft and said power shaft, a second disconnected reverse belt drive between said countershaft and said power shaft, an automatic control means for disconnecting the first mentioned belt drive from said countershaft and connecting the second mentioned belt drive thereto and for periodically reversing said connections, and clutch means mounted on said tumbler tub shaft for selectively connecting said shaft to either the power shaft belt drive or the countershaft belt drive, and a manually controlled belt tightener adapted to operate against the belt of the tumbler tub power shaft drive belt.

6. In a drive mechanism for a dry cleaning machine, a power driven shaft mounted on the machine and provided with a pulley, a countershaft mounted on the machine and supporting three pulleys, one of which is fastened to said countershaft and the other two being idle thereon, a straight belt connecting the pulley on the power driven shaft with one of said pulleys on the countershaft, a crossed belt connecting the pulley on the power driven shaft with another of said pulleys on said countershaft, guides controlling both belts, a worm mounted on said countershaft and driven by one of said idler pulleys, a worm wheel mounted adjacent said worm and operated thereby, and eccentric means carried by said worm wheel and connected to said belt guides for passing one of said belts onto the fixed pulley and passing the other belt onto an idler pulley and for periodically reversing the said operation.

ROBERT McINTYRE CORAM.
